Primary Examiner—T. Chase Nelson*Assistant Examiner*—Michael A Pratt(74) Attorney, Agent, or Firm—Aka Chan LLP(57) CLAIM

The ornamental design for a trailer-hitch flagpole, as shown and described.

DESCRIPTION

FIG. 1 shows a perspective view of a design for a trailer-hitch flagpole.

FIG. 2 shows a right side view of the design.

FIG. 3 shows a left side view of the design.

FIG. 4 shows a back view of the design.

FIG. 5 shows a front view of the design.

FIG. 6 shows a top view of the design.

FIG. 7 shows a bottom view of the first embodiment; and,

FIG. 8 shows a view of the design of the trailer-hitch flagpole when placed in a hitch of an automobile.

The broken lines depict environmental structure and portions of the trailer-hitch flagpole that form no part of the claimed design.
